E. DAVIS

NECKTIE PRESSER AND HANGER

Filed June 22, 1921

INVENTOR
Ella Davis
BY
F. Lehmann
ATTORNEY

UNITED STATES PATENT OFFICE.

ELLA DAVIS, OF BROOKLYN, NEW YORK.

NECKTIE PRESSER AND HANGER.

Application filed June 22, 1921. Serial No. 479,498.

To all whom it may concern:

Be it known that I, ELLA DAVIS, a citizen of the United States, residing at Brooklyn, in the county of Kings and State of New York, have invented certain new and useful Improvements in Necktie Pressers and Hangers, of which the following is a specification.

The main object of this invention is the provision of a necktie press and hanger of simple construction and possessing the quality of simplicity in operation and low cost of manufacture.

The above and other objects will become apparent in the description below, in which like-named characters of reference refer to like-named parts in the drawings.

Referring briefly to the drawings, Fig. 1 is a perspective view of my device in open position.

Fig. 2 is a perspective view of the same in closed position showing the manner of suspending the device.

Fig. 3 is a plan view of the same in open position with the central member folded against one of the end members.

Referring now in detail to the drawings, the numeral 1 represents one of the two end members and 2 the other, said members being pivotally joined by flexible hinge-like members 3 embedded in the edges of said end members. Said end members may be constructed of any desired material, and are preferably of substantially the rectangular form shown.

A central member 4, of the same form as the end members, is provided with slots 5 and 6 situated in staggered relation near the ends of said central member. Eyelets 7 are mounted in the edge of said member, to which the ends of a cord 8 are attached and by which said member may be sus-

pended. Said central member is placed as shown between the two end members without being attached in any way to the end members. A rotatable clip or lock 9 is attached to one of the end members in order to lock all three members in closed position in an obvious manner.

In use, two ties may be pressed in this device. The ties are first wrapped in moistened linen, and then the three members are folded so as to close the device. Before wrapping the ties in the linen, they are, of course, placed on the member 4 as shown in Fig. 3, by passing them thru the slots 5 and 6. Finally, after the lock 9 has been adjusted to prevent opening of the device, the same is suspended by the cord 8. The engagement of the central member 4 with the hinge members 3 allows suspension of the entire device in this manner.

If the device is thus suspended over night, the ties will be found pressed in the morning and ready to wear. Obviously, the ties may be thus mounted in the member 4 without the moistened linen, without departing from the spirit of my invention.

I claim:

A device of the class described comprising a pair of substantially rectangular outer members, flexible means joining said members along their adjacent lateral edges, a separate member of substantially rectangular form having offset openings for holding ties or the like, said separate member being hinged between said outer members, means attached to said separate member whereby the device may be suspended horizontally, and a pivoted clip on the lower edge of one of the outer members for locking all of said members together.

In witness whereof I affix my signature.
ELLA DAVIS.
